Primary Examiner — Garth Rademaker*Assistant Examiner* — Katie Stofko(74) *Attorney, Agent, or Firm* — Patent Law Offices of Rick Martin, P.C.(57) **CLAIM**

The ornamental design for a star-shaped food product, as shown and described.

DESCRIPTION

FIG. 1 is a top perspective view of my new design for a star-shaped food product;

FIG. 2 is a left side elevation view of my new invention, wherein a right side elevation view is a mirrored image thereof;

FIG. 3 is a top plan view of my new invention, wherein a bottom plan view is a reversed view;

FIG. 4 is a front elevation view of my new invention; and, FIG. 5 is a rear elevation view of my new invention.

The broken lines in FIGS. 1-2 and 4-5 illustrate portions of the star-shaped food product that form no part of the claimed design.
